UNITED STATES PATENT OFFICE.

FREDRICK L. JEFFERIES, OF RIVERSIDE, ILLINOIS, ASSIGNOR TO CORN PRODUCTS REFINING COMPANY, A CORPORATION OF NEW JERSEY.

CENTRIFUGAL SEPARATOR.

1,256,697.

Specification of Letters Patent. Patented Feb. 19, 1918.

Application filed July 21, 1917. Serial No. 182,026.

To all whom it may concern:

Be it known that I, FREDRICK L. JEFFERIES, a citizen of the United States, residing at Riverside, in the county of Cook and State 5 of Illinois, have invented certain new and useful Improvements in Centrifugal Separators, of which the following is a specification.

My invention relates to a centrifugal separator and has for one of its primary objects certain improvements in a machine of this type whereby the separation is accomplished more completely and accurately, and more conveniently and economically than with 15 machines heretofore used.

A further object is to provide a centrifugal separator, the operation of which will be accommodated automatically to variations in the inflow of the liquid to the machine and in the proportions between the 20 constituents so that the proper operation of the machine is not affected by such variations which may occur from one cause or another.

The invention consists in the novel improvements, constructions and arrangements for carrying out the above stated objects and such other incidental objects as will appear from the following description.

The invention is illustrated, in a preferred embodiment, in the accompanying drawings wherein—

Figure 1 is a vertical sectional view, with certain parts in elevation, of a separator constructed in accordance with the invention.

Fig. 1^a is a diagram to illustrate the relation of the strata into which the material under treatment is separated.

Fig. 2 is a detail view, in perspective, of one of the partitions or vanes of the revolvable container in which the outlet and vent ducts are formed.

Fig. 3 is a sectional view taken at right angles to the plane of Fig. 1, and on line 3—3 of Fig. 4.

Fig. 4 is a sectional plan on line 4—4 of Figs. 1 and 3, and

Fig. 5 is a plan view of the casting 50 through which the liquid to be separated is to be introduced into the machine.

Like characters of reference designate like parts in the several figures of the drawings.

Referring to the drawings, 10 represents 55 a preferably cylindrical container carried on

a vertical shaft 11 supported on a base 12 with its upper end guided in a bearing in a spider 13 arranged at the upper end of the casing 14. The shaft 11 is revolved by any suitable means. I have shown an electric 60 motor 15 and driving belt 16, the latter extending around a pulley 17 on the motor shaft and pulley 18 on shaft 11. The upper end of shaft 11 is preferably tapered and driven into a tapered opening in a boss 19 65 formed in the bottom of the container 10. 20 is a nut screwed upon a threaded stud 21 at the end of shaft 11. The nut 20 and boss 19 are conical so as to form a spreader for the liquid which enters the machine 70 through pipe 22. The end of pipe 22 extends into an opening 23 in a casting 24 which latter is provided preferably with radial vanes 25. 26 is a cover plate having a central opening 27 to permit the overflow 75 of the lighter constituents of the liquid operated on. The cover plate rests upon a ring 28, angular in cross section, secured to the upper edge of the side wall 29 of the container. Within the container are a plurality of structures 30 (Fig. 2) in radial arrangement, four being shown in the drawings, which provide ducts for the discharge of the heavier constituent of the liquid and are also formed, preferably with vanes or 80 partitions for imparting rotation to the liquid in the container. The duct provided by each of these structures consists of an inwardly extending intake section 31 and an outwardly extending discharge section 32, 85 the end of which latter registers with an opening 33 in the side wall of the container. Associated with each structure 30, and preferably formed integral therewith, is a tubular element 34 extending upwardly from the 90 junction between the duct sections 31, 32. 35 is a web intervening between the tubular element 34 and the discharge duct section 31, the web being preferably formed with a boss 36 for attachment to the cover 100 plate 26. 37 is a web intervening between the duct sections 31 and 32, and 38 a web between outlet duct section 32 and the bottom of the container. The upper ends of the structures 30 are formed with bosses 39 for 105 attachment to the cover plate 26, the heavier constituent entering intake duct section 31 through openings 40 under the bosses. 41 is a stationary casing surrounding the container 110 10 and secured to the casing 14 which incloses

driving shaft 11. The heavier constituent is discharged through ducts 31, 32 into casing 41 and passes through openings 42 on opposite sides of the casing into the discharge pipes 43. Where the machine is used for separating hot liquids or other liquids having objectionable fumes, the discharge pipes 43 are connected, for example, by pipe 44, with a fan conventionally shown at 45 10 (Fig. 2).

46 is a casing which surrounds the casing 41 and the upper end of the container having an opening 47 in the top for the supply pipe 22. 48 is a hopper for the lighter constituent which flows over the cover plate 26, the edge of which projects beyond the casing 41 and drops into the hopper. The hopper may be provided with a screw conveyor 49 for removing the material. The portion 20 of the belt 16 extending through casing 46 is protected by a shield plate 50.

Operation: The container 29 is revolved at a high speed by motor 15. The liquid to be treated enters the machine through pipe 22, is discharged upon the distributing cone 20, and is set in rotation by vanes 25. The liquor builds up in the container so that it forms approximately a hollow cylindrical body with the heavier constituents in a stratum on the outside and the lighter constituent at the inner surface. The main body of the liquor is kept in rotation by vanes 35, 37, 38. The lighter constituent overflows through the central opening in cover plate 26 and passing over the cover plate, drops into the hopper 48. The heavier liquor passes into the intake sections 31 of the overflow ducts through openings 40. When the centrifugal force exerted by the main body 40 of the liquid in the container is sufficient to force the column of liquid in the intake sections or legs 31, (this liquor being denser than the main body of the liquor in the container), beyond the point of intersection between intake leg 31 and discharge leg 32, this point being designated 51, the liquid so displaced into the leg 32 will at once be discharged through opening 33 into the casing 41 and from here the liquor is run out 50 through pipes 43 and the fumes carried away through pipes 44. It will be observed that the overflow point 51 is somewhat farther from the axis of rotation of the machine than the inner edge of the cover plate 26 at 55 which the overflow of the lighter constituent takes place. Although the overflow of the heavier constituent is at point 51 the liquid overflowing at this point is actually taken from a point close to the outer edge of the body where the separation, so far as the heavier constituent is concerned, is most complete. By these arrangements the separation of the liquor into its ingredients, according to gravity, is accomplished very 60 completely and accurately. Each of the sep-

arated constituents is entirely free from any trace of the other constituent. The lighter constituent floats, as it were, as a stratum on the body of heavier material. The overflow points of the latter are on a surface defined by lines *a*—*a*, and this surface, employing the analogy of a floating body, is the surface of the liquid in which the body floats. A portion of the floating body—the lighter ingredient—will be submerged in the liquid in 75 which the body floats—the heavier constituent—and the remainder of the body will stand out of the liquid with its outer surface defined by lines *b*—*b*; and it is this portion which is displaced and overflows the cover 80 plate 26. As a result, the lighter constituent is entirely free from any traces of the heavier constituent. If the lighter constituent is a solid it will be dry. The freedom of the heavier constituent from any traces 85 of the lighter constituent is due to the fact that although the overflow point of the heavier constituent is near the center of the machine, or at least near the inner surface of the annular body of liquid subject to 90 treatment, the liquid which is permitted to overflow at this point is taken from the extreme outer part of the body.

The apparatus just described, besides giving a complete separation as between the constituents of the liquid, accommodates itself automatically to variations in the rate of inflow of the supply and also variations in the character of the liquid, as, for example, in the proportions between one constituent and 100 the other.

If the rate of inflow is diminished from the normal, due to decrease in pressure of the supply liquor or to its greater viscosity, or other causes, the operation of the machine is not affected except that the rate of outflow is diminished. If the inflow be cut off entirely the discharge from the machine will cease. This results from the fact that the discharge of the constituents is brought about entirely by displacement and overflow due to the introduction of fresh liquor. The lighter constituent is freely discharged through the opening 27 as soon as it builds up to the surface defined by this opening. 115 The discharge ducts 31, 32 for the heavier constituent are oversized, that is, their cross sectional area is greater than is required for any normal overflow of the heavier constituent. The function of the vent pipes 34 is to 120 prevent any siphoning action through the discharge ducts 31, 32. If such siphoning action were allowed to take place it would be necessary to accurately control the rate of outflow through legs 32, as, for example, by 125 valves at orifices 33, in accordance with the rate of inflow to the machine, and any variation that there might be in the character of the liquid such, for example, as difference in proportion between the constituents. With 130

the machine operating upon the principle of overflow by displacement no such control is necessary. For example, if the liquid run into the machine contains a greater percent-
5 age of the lighter constituent than is normal, the stratum of the lighter constituent will be deeper, the lighter constituent will tend to float higher in the heavier constituent (again using the analogy of a floating body) with the result that the lighter constituent will be more rapidly discharged. This can be done, under the circumstances, without interfering with the completeness of separation and without disturbing a proper 10 balance in the operation of the machine.

While I have described my invention in a separating apparatus of preferred construction, it is realized that modifications might be made without departure from the principles of the invention. Therefore, I do not wish to be understood as limiting the invention to the particular constructions and arrangements described and claimed, except so far as the claims are specifically so 15 limited.

I claim:

1. A centrifugal separator comprising, in combination, a revoluble container having an opening in the top through which the 20 lighter constituent of the mixture treated overflows, said opening being of greater area than required for any normal discharge therethrough, and means constituting a return bent discharge duct for the heavier constituent also over-sized with respect to the discharge therethrough, the inlet of which is adjacent to the side wall of the container and the outlet of which passes through said side wall, the overflow point at the 25 return bend of said duct being more remote from the center of revolution of said container than the edge over which the lighter constituent overflows.

2. A centrifugal separator comprising, in combination a revoluble container having an opening in the top through which the lighter constituent of the mixture treated overflows, said opening being of greater area than required for any normal discharge therethrough, and means constituting a return 30 bent discharge duct for the heavier constituent also oversized with respect to the discharge therethrough, the inlet of which is adjacent to the side wall of the container and the outlet of which passes through said side wall, the overflow point at the return bend of said duct being more remote from the center of revolution of said container than the edge over which the lighter constituent overflows, 35 said duct having a vent adjacent the bend therein.

3. A centrifugal separator comprising, in combination, a revoluble container having an overflow opening for the lighter constituent and provided with means constituting

a return bent overflow duct for the discharge of the heavier constituent extending into the container from the side wall thereof with its inlet end near said wall and its outlet passing through the same, and means providing said duct with a vent intermediate its inlet and outlet ends. 70

4. A centrifugal separator comprising, in combination, a revoluble container having an overflow opening for the lighter constituent and formed with a duct for discharge of the heavier constituent having an intake section directed inwardly of the container and an outwardly disposed discharge section, which latter extends through the 80 wall of the container, said overflow opening and discharge duct being both oversized in comparison with any normal outflow therethrough; and means for continuously introducing the mixture to be separated into the 85 container so as to produce overflow through said opening and duct.

5. A centrifugal separator comprising, in combination, a revoluble container having an overflow opening for the lighter constituent and formed with a duct for discharge of the heavier constituent having an intake section directed inwardly of the container and an outwardly disposed discharge section, which latter extends through the 90 wall of the container, and means providing said duct with a vent to the atmosphere adjacent the intersection of said duct sections.

6. A centrifugal separator comprising, in combination, a revoluble container having an overflow opening for the lighter constituent and formed with a duct for discharge of the heavier constituent having an intake section directed downwardly and inwardly of the container, and an outwardly 100 and downwardly disposed discharge section which latter extends through the wall of the container.

7. A centrifugal separator comprising, in combination, a revoluble container having an overflow opening for the lighter constituent and formed with a duct for discharge of the heavier constituent having an intake section directed downwardly and inwardly of the container, an outwardly and 110 downwardly disposed discharge section, which latter extends through the wall of the container, and an upwardly extending vent pipe adjacent the intersection of said duct sections.

8. A centrifugal separator comprising, in combination, a revoluble container, a cover plate for the same having a central aperture for discharge of the lighter constituent which is larger than necessary for any normal discharge of said constituent, and a duct for the heavier constituent, also oversized with respect to any normal discharge therethrough which has its inlet end adjacent the 125 side wall of the container, extends in- 130

wardly thereof, then outwardly and discharges through the wall of the container.

9. A centrifugal separator comprising, in combination, a revoluble container, a cover plate for the same centrally apertured for discharge of the lighter constituent, and a duct for the heavier constituent which has its inlet end adjacent the side wall of the container, extends inwardly thereof, then outwardly and discharges through the wall of the container, said duct being formed with a vent at the intersection of its inwardly and outwardly extending portions to prevent siphoning action.

10. A centrifugal separator comprising, in combination, a revoluble container, a cover plate for the same centrally apertured for discharge of the lighter constituent of the mixture treated, a duct for discharge of the heavier constituent which has its inlet end adjacent the side wall of the container, extends inwardly thereof, then outwardly and discharges through the wall of the container, means for introducing the mixture to be separated into the middle of the container, a casing inclosing a portion of said container adapted to receive substance discharged from said duct, and means for receiving the lighter constituent overflowing said cover plate.

11. A centrifugal separator comprising, in combination, a revoluble container, a cover plate for the same centrally apertured for discharge of the lighter constituent of the mixture treated, a duct for discharge of the heavier constituent which has its inlet end adjacent the side wall of the container, extends inwardly thereof, then outwardly and discharges through the wall of the container, means for introducing the mixture to be separated into the middle of the container, a casing surrounding a portion of the container adapted to receive the substance discharged through said duct, said cover plate extending outwardly beyond said casing, and a casing outside of the aforementioned casing provided with means for collecting the lighter constituent as it flows over from said cover plate.

12. A centrifugal separator comprising, in combination, a revoluble container, a cover plate for the same centrally apertured for discharge of the lighter constituent of the mixture treated, a duct for the heavier constituent which has its inlet end adjacent the side wall of the container close under said cover plate, extends inwardly and downwardly thereof, then outwardly and downwardly, discharges through the wall of the container near the bottom and is provided with a vent at the intersection of the inwardly and outwardly extending sections thereof, and means for introducing liquid to be separated into the middle of the container.

13. A centrifugal separator comprising, in combination, a revoluble container, a cover plate for the same centrally apertured for discharge of the lighter constituent of the mixture treated, a duct for the heavier constituent which has its inlet end adjacent the side wall of the container close under said cover plate, extends inwardly and downwardly thereof, then outwardly and downwardly, discharges through the wall of the container near the bottom, a receiving chamber in the bottom of the chamber provided with vanes and openings between said vanes, and a supply pipe extending into said chamber.

14. A centrifugal separator comprising, in combination, a revoluble container, a cover plate for the same centrally apertured for discharge of the lighter constituent of the mixture treated, a duct for the heavier constituent of the mixture treated, a duct for the heavier constituent which has its inlet end adjacent the side wall of the container close under said cover plate, extends inwardly and downwardly thereof, then outwardly and downwardly, discharges through the wall of the container near the bottom, a receiving chamber in the bottom of the chamber provided with vanes and openings between said vanes, a supply pipe extending into said chamber, and a conical spreader in the chamber under said pipe.

15. A centrifugal separator comprising, in combination, a revoluble container, a centrally apertured cover plate for the same, a plurality of radially arranged webs in said container which terminate short of the center of the same, each web being formed with a discharge duct having its inlet end adjacent the side wall of the container close under the cover plate, said ducts extending first inwardly of the container and then outwardly, and discharging through the side wall thereof, said webs being formed with vent passages intersecting said ducts at points adjacent the inwardly and outwardly extending portions thereof.

16. A centrifugal separator comprising, in combination, a revoluble container, a centrally apertured cover plate for the same, a plurality of radially arranged webs in said container which terminate short of the center of the same, each web being formed with a discharge duct having its inlet end adjacent the side wall of the container close under the cover plate, said ducts extending first inwardly of the container and then outwardly and discharging through the side wall thereof, said webs being formed with vent passages intersecting said ducts at points adjacent the inwardly and outwardly extending portions thereof, means providing a receiving chamber in the bottom of the container, a supply pipe extending into said chamber, a casing surrounding a portion of

said container to receive liquid discharged through said ducts, and a casing surrounding the aforementioned casing adapted to receive the lighter constituent overflowing said cover plate.

17. A centrifugal separator comprising, in combination, a revoluble container, a centrally apertured cover plate for the same, a duct which has its inlet end adjacent the side wall of the container, extends inwardly thereof, then outwardly and discharges through the wall of the container, means for introducing liquid to be separated into the middle of the container, a casing inclosing a portion of said container adapted to receive liquid discharged from said duct, means for receiving the lighter constituent overflowing said cover plate, and an exhaust pipe and fan for removing fumes from said casing.

18. A centrifugal separator comprising, in combination, a revoluble container having an overflow opening for the lighter constituent and formed with a duct for the discharge of the heavier constituent having an intake section directed inwardly of the container and an outwardly disposed discharge section, which intersect at a point farther from the center of rotation than the point of discharge of the lighter constituent, and means providing said duct with a vent to the atmosphere adjacent the intersection of said duct sections.

19. A centrifugal separator comprising, in combination, a revoluble container, a cover plate for the same centrally apertured for discharge of the lighter constituent, and a duct which has its inlet end adjacent the side wall of the container, extends inwardly thereof to a point at a greater distance from the center of rotation of the machine than the edge of the cover plate opening, then outwardly and discharges through the wall of the container, said duct being formed with a vent at the intersection of its inwardly and outwardly extending portions to prevent siphoning action.

20. A centrifugal separator comprising, in combination, a revoluble container, a cover plate for the same centrally apertured for discharge of the lighter constituent, and a duct which has its inlet end adjacent the side wall of the container, extends inwardly

thereof to a point at a greater distance from the center of rotation of the machine than the edge of the cover plate opening, then outwardly and discharges through the wall of the container, said duct being oversized with relation to the normal outflow through its outwardly extending portion and being formed at the intersection of said inwardly and outwardly extending portions with a vent to prevent siphoning action.

21. A centrifugal separator comprising a revoluble container provided with overflow openings the effective cross sectional area of which is greater than required for any normal discharge therethrough through which the lighter and heavier constituents are respectively discharged solely by displacement, in combination with means for continuously introducing the mixture to be treated into said container so as to effect said displacement.

22. A centrifugal separator comprising a revoluble container provided with overflow openings through which the lighter and heavier constituents are respectively discharged solely by displacement, in combination with means for continuously introducing the mixture to be treated into said container so as to effect said displacement, both said overflow openings being near the inner surface of the body of material subject to treatment in the container, and means providing an inclosed duct leading from the outer portion of said body to the overflow opening for the heavier constituent.

23. A centrifugal separator comprising a revoluble container provided with overflow openings through which the lighter and heavier constituents are respectively discharged solely by displacement, in combination with means for continuously introducing the mixture to be treated into said container so as to effect said displacement, both said overflow openings being near the inner surface of the body of material subject to treatment in the container, and means providing an inclosed duct leading from the outer portion of said body to the overflow opening for the heavier constituent, the latter opening being farther from the center of rotation of the container than the opening for the lighter constituent.

FREDRICK L. JEFFERIES.
